UNITED STATES PATENT OFFICE.

CLARENCE JOHN LAW, OF BALMAIN, NEAR SYDNEY, NEW SOUTH WALES, AUSTRALIA,
ASSIGNOR TO ALBERT HERBERT THOMPSON, OF SYDNEY, NEW SOUTH WALES,
AUSTRALIA.

OIL-MIST VAPORIZER ATTACHMENT FOR ENGINE CARBURETORS.

Application filed July 24, 1923. Serial No. 653,559.

To all whom it may concern:

Be it known that I, CLARENCE JOHN LAW, subject of the King of Great Britain, residing at 103 Rowntree Street, Balmain, 5 near Sydney, New South Wales, Australia, have invented certain new and useful Improvements in Oil-Mist Vaporizer Attachments for Engine Carburetors, of which the following is a specification.

10 This invention relates to apparatus for heating fuel gas mixtures between a carburetor and the gas inlet passage of an internal combustion engine. It consists in a tubular fitting in which during the starting 15 of the engine the mixture is heated by electrical means and during running is heated by means of engine exhaust gases. The novelty consists in constructing the heater fitting with its interior surfaces electrically 20 non-conductive, and winding and lacing a bare electrical conductor wire over said surfaces, said wire being terminally connected to a storage battery through a switch which controls a starting motor associated with 25 the engine.

In the accompanying drawings,—

Fig. 1 is an elevational view with a portion in fragmentary section showing a hot box in the exhaust line of an engine, said 30 box having alternative exhaust pipe connection sockets;

Fig. 2 is a transverse section on the line 2—2 Fig. 1;

Fig. 3 is an end elevational view of the 35 tubular fitting in the hot box showing the heater coil winding; and

Fig. 4 is a diagrammatic view explanatory of the electrical heater circuit.

10 is a hot box which is introduced into 40 the exhaust line of the engine by connections at opposite sides of it. For the purposes of illustration, alternative exhaust pipe connections 11—12 are shown, the direction of flow of the hot exhaust gases being 45 indicated by an arrow if the exhaust gas enters through the pipe 8 and passes away through the pipe 12. In the normal arrangement the exhaust gas enters through the pipe 8 and passes away through the 50 socket connection 9, the sockets at 11 and 12 being then plugged; the unused sockets are plugged whatever the pipe arrangement 55 may be.

13 is a valve in the exhaust circuit, 14 a

lever on the valve spindle, and 15 a connection to any appropriate control device 55 within reach of the driver's hand. When the valve 13 is fitted, the hot circuit to the box 10 should be a by-pass from the main exhaust pipe from the engine. The function of the valve 13 is to control the temperature of the heater device during the running of the engine, the engine driver being enabled, by means of the control, to vary the temperature of the induction gas 60 according to his judgment.

16 indicates the outer wall of an engine manifold. The hot box 10 has a central orifice formed through it in alignment with the manifold intake aperture 17. An open 70 cylinder 18 is fitted into this central orifice in the hot box 10, the fitting being facilitated by an end flange 19 on the cylinder which is spigoted into one wall of the hot box 10, a tight closure being made by a 75 gasket 20 against the engine wall 16, and a joint with the uptake pipe 21 from the carburetor being completed by a gasket 22, said gaskets 20 and 22 covering the joints. The cylinder 18 is crossed by two flat 80 narrow tubes 23—24 extending through its walls. Exhaust gas in the box 10 circulates over the walls of the cylinder 18 and through the cross tubes 23—24. 25 is an inwardly disposed flange at that end of the 85 cylinder 18 which is nearest the engine wall. The flange 25 is pierced symmetrically with holes 26. Interiorly the cylinder 18 is surfaced on its interior aspect with electrically insulating fire enamel; this enamel covers 90 not only the interior surface of the cylinder 18, but also the outer surfaces of the flat cross tubes 23—24 and the flange 25, and it lines the holes 26 in the flange 25.

The electrical heater unit, consisting of 95 a bare wire of nickel-chrome alloy 27, is wound helically around the flat cross tubes 23—24 and is reeved to and fro through the holes 26 in the flange 25 to form a wire grid across the engine induction aperture 17. 100 The cross section of the nickel-chrome wire 27 is proportioned according to its length so that said wire will be brought to a high temperature by the current obtained from the storage cell 28, but so as not to bring 105 it to a glowing temperature whereby ignition of the fuel might be caused whilst it is passing through the cylinder 18. The

ends of the wire 27 are brought out through a protective sheath 29 of asbestos, this sheath being detachably fixed in a stuffing box fitting 30 in the side of the uptake pipe 21 from the carburetor. One terminal of the wire 27 is connected to the battery lead 31 and the other terminal of it to the battery lead 32. These leads are branched in parallel with the starting motor 33, so that current flows through the wire 27 only whilst the starting motor is held in operation by the closing of the starter switch 34.

When starting up an engine in cold condition, as soon as the starter switch 34 is closed, current from the battery 28 flows through the heater wire 27, so that the wet gas which is delivered from the carburetor is preheated in passing over the hot wires 27; easy starting is thus facilitated. Immediately the engine starts up, the switch 34 is thrown out, and current is no longer taken through the wire 27; thereafter heat derived from exhaust gases passing through the chamber 10 is utilized to heat the walls 25 of the cylinder 18 and the cross tubes 23-24, the driver controlling the temperature of the induction mixture during running by adjusting the valve 13.

The device therefore functions automatically, co-acting with the starter motor to ensure warming up of all gas drawn into the engine, and cutting out the electrical heating element, and utilizing heat from

exhaust gases immediately the engine is started, and during running of the engine. 35

Instead of constructing the cylinder 18 and its integral cross tubes 23-24 of metal fire enamelled on the interior aspect to ensure electrical insulation where it is touched by the bare wires which form the 40 electrical heater unit, the cylinder and its cross tubes may be constructed of porcelain; in this case it is desirable to form the flange 25 is a separate ring inset into a spigoted end in the cylinder 18, but it is undesirable 45 to use porcelain for the purpose, in view of the risk of cracking it in bolting up the heater and carburetor to the engine structure.

What I claim as my invention and desire 50 to secure by Letters Patent is:—

A gas fuel mixture heater comprising a metal casing adapted to be fitted in the exhaust gas pipe line of an engine, a metal cylinder in the gas induction line, flat 55 narrow tubes crossing said cylinder and terminally open to said casing, a coating of electrically insulating fire enamel upon the whole interior aspect of said casing and the whole exterior aspect of said tubes, and 60 an electrical resistance heater winding of bare wire wound over said tubes.

In testimony whereof I affix my signature.

CLARENCE JOHN LAW.
